(57) **CLAIM**

The ornamental design for a ball picker, as shown and described.

DESCRIPTION

FIG. 1 is a front, left perspective view of a ball picker in the first state, showing my new design;

FIG. 2 is a rear, right perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, left perspective view of a ball picker in the second state;

FIG. 10 is a rear, right perspective view of a ball picker in the second state;

FIG. 11 is an enlarged view of detail 11 in FIG. 1;

FIG. 12 is an enlarged view of detail 12 in FIG. 5; and,

FIG. 13 is an enlarged view of detail 13 in FIG. 7.

The dashed broken lines in the figures are for the purposes of illustrating portions of the ball picker that form no part of the claimed design.

The dash-dot-dash broken lines are for notating enlarged views and form no part of the claimed design.
